(57) **CLAIM**

The ornamental design for a bowl and lid assembly, as shown and described.

DESCRIPTION

1.1 is a top plan view of a bowl and lid assembly in a disassembled configuration, showing our new design;

1.2 is a bottom plan view thereof;

1.3 is a side view thereof;

1.4 is a lower perspective view thereof;

1.5 is a top perspective view thereof;

1.6 is a top perspective view thereof in an assembled configuration; and

1.7 is a lower perspective view thereof in an assembled configuration.
